DISPOSABLE UMBRELLA FOR EMERGENCY
USE

Edward T. McPartland, New York, N.Y.

Application February 3, 1950, Serial No. 142,292

2 Claims. (Cl. 135—19.5)

1

This invention relates to a disposable umbrella for emergency use.

It is the principal object of this invention to provide an umbrella which is suitable for emergency use and which is disposable at the termination of the emergency. Although this is the principal object, it will be appreciated that the umbrella herein claimed is sufficiently durable so that it may be used time and time again, before it is ultimately discarded. The question of durability may be left to the manufacturer. More durable materials will naturally cost more and less durable materials will normally cost less and the ultimate selling price of the umbrella will be an important factor in determining the nature of the material to be used.

An umbrella made in accordance with this invention for strictly emergency use and intended to be discarded at the end of the emergency period, may be made of relatively non-durable materials such as paper or cardboard, treated with paraffin or other suitable substances to render it waterproof, or at least highly resistant to disintegration in the presence of water. An umbrella made in accordance with the present invention and intended for non-emergency as well as emergency use may be made of more durable and perhaps more expensive materials, such as Celluloid, plastics and even sheet aluminum.

Another object of this invention is the provision of a disposable umbrella of the character described which may be made very inexpensively by mass production methods. More specifically, the several parts of the present umbrella may be die-cut to appropriate shape, and one of the parts thereof, namely the canopy, may be pre-scored in long, continuous sheets before the die-cutting operation, leaving only the assembling and folding operations for the last. The assembling operations are neither complicated or difficult, since they consist, generally, of only one step, namely the step of affixing the handle to the canopy. This may be done in any suitable, conventional manner and by any suitable, conventional means. Metal staples may be used or a suitable cement or the like.

A further object of this invention is the provision of a disposable umbrella of the character described which is readily foldable to compact proportions. Many disposable umbrellas of the prior art are non-collapsible or non-foldable and they are accordingly difficult to manage and handle. They must be shipped, stocked and sold in open condition, with consequent waste of valuable shipping and storing space insofar as

2

the shipper, distributor and retailer are concerned, and with corresponding waste of display space in the retail establishment. This is especially true of small newsstands located at train, car and bus stations and stops where disposable umbrellas would be most likely to sell. A non-collapsible and non-foldable umbrella is also inconvenient for the ultimate consumer since it would require entering crowded quarters with a wet, unwieldy contraption which would cause considerable annoyance and discomfort to others. It would be unthinkable, for example, to take a wet, non-collapsible umbrella into a crowded street-car or bus. And yet that is what many designers of disposable umbrellas of the prior art would have the users of their umbrellas do. An umbrella made in accordance with the present invention is fully foldable to conserve shipping and storing space and for the purpose of rendering it convenient to use in the hands of the ultimate consumer.

Still another object of this invention is the provision of a sun-shield or parasol which is made in accordance with the principles of the present invention. The present invention is applicable not only to umbrellas which shield against the rain but also to umbrellas which shield against the sun. Disposable umbrellas of the character herein described and claimed may be used to good advantage at beaches, in parks and the like. Umbrellas made in accordance with the present invention are also conducive to use by children during the course of their play-time activities.

35 A still further object of this invention is the provision of a ribless umbrella. It is a well-known fact that the outwardly projecting ends of umbrella ribs have caused many an injury to the person carrying the umbrella as well as to others in the immediate vicinity. Injuries to the eyes have on many occasions been caused by these outwardly projecting ribs. Umbrellas made in accordance with the present invention are provided with stiffening means other than ribs and hence the danger of injury caused by ribs in conventional umbrellas is thereby avoided.

Briefly speaking, umbrellas made in accordance with the present invention comprise but two parts: a canopy and a handle to support the canopy. The canopy is of three types: the first type is entirely dependent upon the handle to maintain it in open or operative condition. The second type is a combination of the first and third types since a handle similar to that of the first type is employed and such handle is ma-

terially assisted in its function by the structural strength inherent in the canopy. The third type can maintain itself in open or operative condition without external support. The handle which is employed in connection with the first and second type of canopy accordingly performs two functions: the first is to maintain the canopy in open, operative condition; the second is to provide a support whereby the person using the umbrella may hold the canopy in operative position. The handle for the third type of canopy is used principally to enable the person making use of the umbrella to hold the canopy in operative position, but in addition to this function, it helps maintain the canopy in open condition.

Preferred forms of this invention are illustrated in the accompanying drawing in which:

Fig. 1 is a plan view of an umbrella made in accordance with the first form of this invention.

Fig. 2 is a perspective view of said umbrella, partly broken away and in section, and showing said umbrella in partly folded condition.

Fig. 3 is a similar view showing the canopy in bowed condition.

Fig. 4 is a bottom view of said umbrella as viewed in the direction of arrows 4—4 of Fig. 3.

Fig. 5 is an enlarged fragmentary view similar to that of Fig. 3, showing how the handle may be folded to give the canopy its bowed, operative shape.

Fig. 6 is a sectional view on the line 6—6 of Fig. 5.

Fig. 7 is a view of the umbrella shown in the first six figures of the drawing, showing it in partly folded condition.

Fig. 8 shows the same umbrella folded still further.

Fig. 9 shows the same umbrella in completely folded condition.

Fig. 10 is a plan view of an umbrella made in accordance with a second form of this invention.

Fig. 11 is a side edge view of said umbrella before the canopy is bowed to operative position.

Fig. 12 is a sectional view showing how the handle of the said umbrella is held in the hand to support the umbrella in operative position.

Fig. 13 is a bottom view of said umbrella looking in the direction of arrows 13—13 of Fig. 12.

Fig. 14 is a plan view of an umbrella made in accordance with a third form of this invention, the canopy thereof being partly broken away to expose an overlapped portion thereof.

Fig. 15 is a side view thereof showing its conical shape.

Fig. 16 is a perspective view of said umbrella looking upwardly at the under side thereof.

Fig. 17 is a fragmentary view of said umbrella showing the handle construction thereof.

Fig. 18 is a sectional view taken on the line 18—18 of Fig. 17.

Fig. 19 is a bottom view of an umbrella made in accordance with the first form of this invention but showing a modified folding line arrangement.

Fig. 20 is a similar view of another umbrella made in accordance with the first form of this invention, showing still another modified arrangement of the folding lines.

Fig. 21 is still another similar view of an umbrella made in accordance with the first form of this invention with a further modified arrangement of the folding lines.

Referring now to the first form of this invention as shown in Figs. 1 to 9 inclusive, it will be

noted that an umbrella is provided which consists of but two elements: a canopy 20 and a handle 21 which is connected to said canopy by means of staples 22. The canopy comprises a disc-shaped sheet of suitable material, such as paraffined cardboard which is provided with a plurality of fold lines 23. The handle 21 comprises a strap which may also be made of the same or similar material, or for that matter, other material. It must be made of fairly stiff material, if the canopy is of flexible material, to prevent the canopy from assuming an inverted U-shape. Conversely, the handle need not be of stiff material if the canopy itself is of fairly rigid material. The handle is fastened at both ends by means of staples 22 or other fastening means near the center of said canopy 20, in such a position that its perpendicular bisector, or a similar imaginary line through its midsection, traverses all fold lines of the canopy. Fig. 1 shows the preferred location of the handle when used with a canopy containing a central fold, and all folds in parallel relation. The handle may be placed in the exact center on canopies which omit the central fold. In their relaxed states, the canopy and the handle are both flat against each other in the manner shown in Fig. 2 and the canopy does not have that bowed shape required to keep the canopy in open or operative condition. But when the handle is itself bowed in the direction away from the canopy, as witness Fig. 3, the effect is to bring the two ends of the handle closer to each other and thereby to produce a bowed effect in the canopy. The axis of the bowed canopy extends transversely of fold lines 23 and hence a strong, rigid structure results.

Handle 21 may be held in its bowed state by simply grasping it and inserting the fingers between it and the canopy and by the same token the canopy will itself assume its bowed shape. It will be noted in Figs. 4, 5, and 6, that the handle may be provided with a longitudinal folding line 25 and with two V-shaped folding lines 26 at the two ends of the said longitudinal folding line. The two sides of the handle which are separated from each other by means of said longitudinal folding lines may then be folded over toward each other upon said longitudinal folding line in the manner shown in said Figs. 4, 5 and 6. This has the effect of further drawing the two ends of the handle toward each other to further accentuate the bowed condition of the canopy.

It has been stated that the canopy 20 is provided with a plurality of folding lines 23. It can be appreciated that canopies containing only one fold line may be made. Canopies which contain more than one fold line should preferably have such fold lines in parallel relation to each other, for parallel lines simplify manufacture, suggest the preferred method of folding, and permit the folded canopy to have a neat, compact appearance. While the fold lines need not necessarily be parallel, there are certain limitations that are essential to the proper functioning of the umbrella. The fold lines must not intersect, nor meet at any point or points other than on the perimeter. They must be of such length and direction that each is traversed by a diametric line, or a straight line which passes near the center of the canopy. Each fold line must be made in such a manner that it can be folded easily in either direction, thereby eliminating the V-shaped ridges that would otherwise be present in the canopy. If these ridges were not corrected they might easily distort the shape of the umbrella to

such a degree as to render it unserviceable. They are made to fold easily in either direction by scoring both surfaces in the conventional manner, making incisions on both surfaces, or cutting completely through each fold and then covering each fold with a suitable tape. These folding lines may be incorporated into the material of which the canopy is made either before or after the canopy is die-cut to appropriate shape. In the preferred forms of this invention canopy 20 and all of the other canopies of which use may be made, are of circular or disc shape, but this should be taken purely as illustrative of the present invention and not as limitative thereof, since the canopies may be made to assume other shapes equally as well, depending upon individual preferences and requirements. If the material of which the canopy is made comes in long lengths, the folding lines 23 may advantageously be pressed or cut into the material before it is die-cut. If the material comes in short lengths it may be found desirable to incorporate the folding lines therein following the die-cutting operation. It should also be understood that the canopy need not necessarily be die-cut one at a time but instead layers of the material may be die-cut simultaneously and by means of the same die-cutting operation.

The preferred manner in which canopy 20 may be folded is clearly shown in Figs. 7, 8 and 9. Panels 23a and 23b may be folded over upon panels 23c and 23d respectively. Panels 23c and 23d may be folded over upon panels 23e and 23f respectively. Panels 23e and 23f may be folded over upon panels 23g and 23h respectively. And finally panels 23a, 23c, 23e, and 23g may be folded over upon panels 23b, 23d, 23f, and 23h. The folded canopy, shown in Fig. 8, may be folded over upon itself on a transverse folding line as shown in Fig. 9. It can be appreciated that canopy 20 may be folded by a variety of other methods since the folds are biflex, it does not have a conical shape, and the spacing between folds may vary.

Turning now to the second form of this invention and to Figs. 10 to 13 inclusive, it will be seen that a canopy 30 is provided, having a handle 31 affixed thereto by means of staples 32 or by any other conventional means. Canopy 30 is similar to canopy 20 above described in that it is made of waterproof or waterpoofed material and further in that it is made of a flat sheet containing one or more fold lines 33a, 33b, 33c, 33d, 33e, 33f and 33g which are subject to the same limitations outlined for canopy 20. Canopy 30 must be folded in a manner similar to that illustrated for canopy 20 and therefore additional care is required in spacing the folds. In order to fold canopy 30 properly the distance between fold 33c and 33d should exceed the distance between fold 33c and 33b, such distances being measured along a line drawn perpendicular to fold 33c at any point. The same reasoning would apply to folds 33d, 33e and 33f, and allowance must be made for the seam which is made in the following manner. A radial slit is formed in the canopy and the edges are brought into overlapping position and held in place in such position by means of a staple 35 or by any other suitable means. The effect of overlapping the edges of the canopy on both sides of slit 34 is to cause the canopy to assume a somewhat conical shape. The conical shape of canopy 30 is of material assistance in preventing its collapse, but canopy 30 is not

self-supporting since it will collapse along its central fold. A handle, similar to that used on canopy 20 must be employed to bow the central fold sufficiently to prevent its collapse. Any other folds will be automatically bowed to conform to the conical shape of the canopy, and the handle will accentuate their bowed condition.

Handle 31 is H-shaped and there are accordingly four staples 32 to fasten the four ends of said H-shaped handle to the canopy. It is located near the center of the canopy in such a way that a perpendicular line, through the mid-section of longitudinal portions 32b and 32c, will traverse all fold lines of the canopy. The preferred location for the handle, when parallel fold lines are used in the canopy, is illustrated in the drawing. It will be noted in the drawing that the cross member 32a of the handle intersects the centermost folding line 33d at right angles thereto and that the two longitudinal portions 32b and 32c thereof are equally spaced from said centermost folding line in parallel relation thereto. Hence it will be seen that handle 31 is centrally disposed relative to canopy 30 whereas handle 21 was disposed on one side of the centermost folding line of canopy 20.

Each longitudinal portion 32b, 32c of handle 31 performs the same function as does handle 21. In other words, when longitudinal portions 32b and 32c are bowed in the direction away from the canopy, they tend to contract in length and thereby assist in the task of maintaining the canopy in open condition. Cross member 32a is really the handle proper and it is provided with a centrally extending folding line 32d upon which it may be folded lengthwise upon itself in the manner shown in Fig. 12. In the drawing, fold line 32d is shown as the perpendicular bisector of longitudinal portions 32b and 32c. While this is desirable, it is not essential to the proper functioning of handle 31.

It is understood that when cross member 32a is located on the geometric center of the canopy, as illustrated, it would interfere with the folding of the canopy to the proportions illustrated for canopy 20 in Fig. 9. However, it can be folded to compact proportions by making the final fold to one side of cross member 32a. When cross member 32a is not located on the geometric center of the canopy, the final fold of the folding process can be made as illustrated in Fig. 9 for canopy 20. Cross member 32a may also be cut out along its respective side edges so that when it is folded over upon itself on folding line 32d, there will be more space between it and the canopy to accommodate the fingers of the person holding the handle. This is clearly shown in Fig. 12.

The third form of this invention, shown in Figs. 14 to 18 inclusive, is provided with a canopy 40 which is similar to canopy 30 except that it has no centrally extending folding line. It does, however, have a plurality of folding lines 41 which are formed on both sides of the center of the canopy. A radial slit 42 is formed in canopy 40 and the edges of the canopy on both sides of the slit are placed one upon the other, in overlapping relation, and they are held in such position by means of a suitable adhesive or cement 43 or any other suitable fastening means.

On canopies 20 and 30, a handle was employed to effect a bow in the fold lines, thereby preventing their collapse. The fold lines of canopy 40 are naturally bowed, since they must conform to the curved surfaces of the cone. Hence it is that

canopy 40 maintains itself in the open or operative condition without external assistance.

A handle 45, similar to handle 21, is fastened to canopy 40 by means of staples 46 at both ends of said handle. When handle 45 is bowed in the direction away from the canopy, the straight line distance between its two end portions, tends to contract or decrease and the effect is to assist the canopy in maintaining its conical form, and even to accentuate its said conical form. Handle 45 may be maintained in bowed condition by the hand which holds it to support the canopy. A locking member 47 may be provided to hold the handle in bowed condition without manual assistance. This locking member 47 comprises a strip of relatively stiff material which is fastened to the canopy by means of staples 48 at both ends of said locking member. Locking member 47 is situated to extend transversely of the handle and underneath said handle. The length of locking member 47 exceeds the distance between its two end portions as they are affixed to the canopy and hence transverse fold lines 49 and 50 are provided so that said handle may be folded flat upon itself to lie flat against the canopy. Locking member 47 also has another transverse folding line 51 and a fourth transverse folding line 52. When the locking member is folded on all of its said transverse folding lines in the manner shown in Fig. 16, it constitutes a brace which engages the handle and urges it into bowed shape. By the same token it tends to strengthen the conical structure of the canopy and that is one of its functions. The other function is to maintain the handle in such position that it may readily be grasped.

Figs. 19, 20 and 21 show that in all cases the folding lines must be so disposed that all are traversed by at least one diametric line D—D and the handle must be so disposed that the perpendicular bisector of its length B—B traverses all the said folding lines. In these three figures, canopies 26a, 26b, and 26c are respectively shown, these canopies being similar to canopy 26 with the sole exception that the folding lines and the handle are disposed differently. In Fig. 1 the folding lines are all parallel to each other and equally spaced from each other. In Fig. 21 the folding lines are parallel to each other but their spacing is not equal. In Fig. 20 the folding lines converge 50

to a point at the edge of the canopy. In Fig. 19 the folding lines converge but do not meet on the canopy.

It will be understood that the foregoing is descriptive of three forms of this invention and that there are other forms which are encompassed within the broad scope and spirit of the invention. For example, any one of the three handles which are shown in the drawing may be used in connection with any one of the three canopies which are shown in the drawing. Also other forms of handle and other forms of canopy may be provided within the scope of this invention.

15 The invention is claimed as follows:

1. A disposable umbrella comprising a canopy and a handle fastened to said canopy, said canopy being slit radially of itself with the edges on both sides of the slit fastened together in overlapping relationship to provide the canopy with a conical shape, said canopy being provided with a plurality of spaced, parallel folding lines on which it is foldable, said folding lines being disposed in parallel relation to said handle, whereby 20 the handle may be bowed to assist the canopy in maintaining its conical shape.

2. In a disposable umbrella of the character described, a canopy having a plurality of spaced, parallel, folding lines formed therein so that 25 said canopy may be folded upon itself, said canopy being slit radially of itself and its edges adjacent said slit being fastened together in overlapping relationship to give the canopy a conical shape.

35 EDWARD T. McPARTLAND.
